(57) **CLAIM**

We claim the ornamental design for the overlay tray, substantially as shown and described.

DESCRIPTION

FIG. 1 is a top, front, left side perspective view of an overlay tray, according to a first embodiment;
 FIG. 2 is a top plan view of the overlay tray, according to the first embodiment;
 FIG. 3 is a bottom plan view of the overlay tray, according to the first embodiment;
 FIG. 4 is a right side elevational view of the overlay tray, according to the first embodiment;
 FIG. 5 is a left side elevational view of the overlay tray, according to the first embodiment;
 FIG. 6 is a front side elevational view of the overlay tray, according to the first embodiment;
 FIG. 7 is a rear side elevational view of the overlay tray, according to the first embodiment;
 FIG. 8 is an enlarged front side elevational view of a portion of the overlay tray, as identified in FIG. 6, according to the first embodiment;
 FIG. 9 is a top, front, left side perspective view of an overlay tray, according to a second embodiment;
 FIG. 10 is a top plan view of the overlay tray, according to the second embodiment;
 FIG. 11 is a bottom plan view of the overlay tray, according to the second embodiment;
 FIG. 12 is a right side elevational view of the overlay tray, according to the second embodiment;
 FIG. 13 is a left side elevational view of the overlay tray, according to the second embodiment;
 FIG. 14 is a front side elevational view of the overlay tray, according to the second embodiment;
 FIG. 15 is a rear side elevational view of the overlay tray, according to the second embodiment; and,
 FIG. 16 is an enlarged front side elevational view of a portion of the overlay tray, as identified in FIG. 14, according to the second embodiment.
 The evenly dashed broken lines of the various embodiments of the overlay are directed to environment and are for illustrative purposes only; the evenly dashed broken lines form no part of the claimed design.
